UNITED STATES PATENT OFFICE.

WILLIAM O. JOHNSON, OF BLUNT, SOUTH DAKOTA.

ATTACHMENT FOR COMBINATION-LOCKS.

No. 919,177.

Specification of Letters Patent. Patented April 20, 1909.

Application filed April 1, 1908. Serial No. 424,578.

To all whom it may concern:

Be it known that I, WILLIAM O. JOHNSON, a citizen of the United States, residing at Blunt, in the county of Hughes and State of South Dakota, have invented certain new and useful Improvements in Attachments for Combination-Locks; and I do hereby declare the following to be a full, clear, and exact description of the invention, such as will enable others skilled in the art to which it appertains to make and use the same.

This invention relates to attachments for combination locks and has primarily for its object to provide a novel attachment to facilitate the turning of the bearing knob of the dial plate employed in conjunction with a combination lock.

It is furthermore an object of the invention to provide a novel attachment of this character which may be easily applied or removed from the knob.

It is a further object of the invention to provide a novel device of this character possessing such resiliency as to automatically bind against the knob or shank thereof to be rotated.

It is also an object of the invention to provide a novel device of this character that will be simple in construction, efficient in practice and comparatively inexpensive to manufacture.

With the above and other objects in view, the invention consists in the details of construction and in the novel arrangement and combination of parts to be hereinafter referred to.

In describing the invention in detail, reference will be had to the accompanying drawings forming part of this specification, wherein like characters of reference denote corresponding parts in the several views, and in which,

Figure 1 is a view in elevation of a fragment of a safe door, showing the invention in applied position. Fig. 2 is a view in side elevation of the invention, detached.

In the drawings, 1 denotes a fragment of a safe door having thereon an annular rib 2, within which rotates the dial plate 3,

which is carried by the knob, or more particularly, the shank thereof, indicated in Fig. 1 by dotted lines. The attachment for engaging the shank 5 is formed from a single piece of steel wire having one end bent to form a hook 6, the distance between the free end portion of the hook and the body or stem 7 being less than the diameter of the knob or shank which it is intended to engage. This free end portion 8 is curved outwardly in order that it may be readily applied to the shank, said curved portion 8 acting as a guide, as will, it is thought, be fully appreciated.

The end portion of the body 7, opposed to the hook 6, is bent at approximately right angles to form an operating handle 9. This angular portion 9 is also arranged on a plane at right angles to the plane of the hook 6.

As the attachment is formed of steel wire, it possesses a certain amount of natural resiliency which will readily permit the hook being passed over the shank 5 of the knob and this resiliency will further cause the hook to bind against the shank 5 when in applied position, so that when the attachment is rotated by grasping the handle 9, it will cause the knob to readily rotate in the desired direction.

I claim:

As a new article of manufacture, an operating attachment for the knob of a dial consisting of a single piece of wire having one end portion bent to form a hook, said bent portion extending beyond either side of the plane of the body of the wire and the opposite end portion being bent in a plane at right angles to the plane of the hook, the free end portion of the hook being arranged on an outward curve with relation to the body.

In testimony whereof I have signed my name to this specification in the presence of two subscribing witnesses.

WILLIAM O. JOHNSON.
